UNITED STATES PATENT OFFICE.

ANDREW EKMAN, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

DOOR LATCH.

Application filed February 19, 1925. Serial No. 10,207.

To all whom it may concern:

Be it known that I, ANDREW EKMAN, a subject of the King of Sweden, residing at Grand Rapids, in the county of Kent and 5 State of Michigan, have invented new and useful Improvements in Door Latches, of which the following is a specification.

The present invention relates to door latches; and its object is to provide improved 10 means for unlatching the same from the opposite side of the door.

This and any other and more specific objects hereinafter appearing are attained by, and the invention finds preferable embodiment in, the structure or structures herein- 15 after particularly described in the body of this specification and illustrated by the accompanying drawings, in which:—

Figure 1 is a front or face view of a door 20 latch;

Figure 2 is an end view thereof;

Figure 3 is a transverse horizontal sec- 25 tional view of a portion of a swingable door and of its jamb, showing in top plan view the said latch mounted on the door's outer side, and showing means for unlatching the same from inside the door;

Figure 4 is a face view of a block or metal casting and levers fulcrumed thereon;

Figure 5 is a right-hand side view of the same;

Figure 6 is a front or face view of another form of door latch;

Figure 7 is an end view thereof; 35 Figure 8 is a transverse horizontal sec- tional view of a portion of a swingable door and of its jamb, showing in plan view the latch shown in Figures 6 and 7, and showing a modified construction of the means for

unlatching the same from the door's oppo- 40 site side, such modified form of said means being particularly adapted to operate in connection with the form of latch shown in Figures 6, 7 and 8;

Figure 9 is a vertical sectional view of said door and jamb; and

Figure 10 is a front or face view of a block or metal casting and the levers of said modified construction fulcrumed thereon.

50 In the accompanying drawings, a swing- ably mounted door—as the refrigerator door 1—is shown, carrying a latch 2 mounted on its outer side or surface adjacent the door's "free" edge. The jamb or 55 frame of the door adjacent its free edge, and

carrying the latch's keeper 3 is indicated at 4. In Figures 1, 2 and 3 a latch of the form or type having a slideable latching bolt 5 is shown, while in Figures 6, 7, 8 and 9 a latch having a swinging or lever form of 60 latching bolt 5¹ is illustrated, the form of the means for unlatching the latch from inside the door being somewhat different in Figures 3, 4 and 5 from that illustrated in Figures 8, 9 and 10. 65

In the construction or form seen in Figures 1-5: A block or metal casting 6 secured as by screws passed through its openings 7 to the inner side of the door, carries levers 8 and 9 fulcrumed thereon, at 10 and 11, at 70 right angles to each other. The short arm 12 of lever 8 engages under the arm 13 of lever 9. A rod 14 extends through the door, being slideable in the opening 15 therethrough. The outer end 16 of the rod abuts on the 75 inner side of the operating lever or handle 17 of the latch, and its inner end 18 abuts on the other arm 19 of the lever 9. It will be seen that, the block 6 being secured on the inner side of the door at a convenient ele- 80 vation from the floor, the long arm 20 of lever 8 may be readily pressed by the shoulder of a man carrying a heavy burden out of the refrigerator room, and thus the door may be unlatched and pushed open, without 85 the necessity of his laying down his burden or using his hands for this purpose.

Another form or modified construction of the unlatching means especially adapted for use in connection with latches having swing- 90 ing or lever-latch bolts is shown in Figures 6-10: In this form the lever 21 fulcrumed at 22 on the block or casting 6¹ has a long arm 23 extending through an opening 24 in the door and engaging the upper side of 95 the handle portion of the latching-lever 5¹ of the latch 2¹, the short arm 25 of this lever 21 being engaged by the short arm 12¹ of the lever 8¹, fulcrumed at 10¹, whose long arm 20¹ is adapted to be pressed toward the 100 door to operate the unlatching means.

A guiding extension 26 of the casting or block 6 extends through an opening 27 in lever 9 as shown in Figures 4 and 5.

The invention being intended to be point- 105 ed out in the claims, is not to be limited to or by details of construction of the partic- ular embodiment or embodiments thereof illus- trated by the drawings or hereinbefore described.

I claim:

1. In combination with a swingable door; a latch having an operating lever fulcrumed on the outer side of the door; a lever fulcrumed on the inner side of the door; a lever fulcrumed on the inner side of the door and having an arm engaged by an arm of the second-mentioned lever; a slidable rod extending through the door and engaging the first-mentioned lever and engaged by the other arm of the third-mentioned lever to swing the first-mentioned lever to unlatching position by the swinging movement of the second-mentioned lever.
- 15 2. In combination with a swingable door: a latch having an operating lever fulcrumed on the outer side of the door; a block car-

ried by the inner side of the door; a lever fulcrumed on the block; a lever fulcrumed on the block at right angles to the second-mentioned lever's fulcrum, and having an arm engaged by an arm of the second-mentioned lever; a slidable rod extending through the door and engaging the first-mentioned lever and engaged by the other arm of the third-mentioned lever to swing the first-mentioned lever to unlatching position by the swinging movement of the second-mentioned lever.

In testimony whereof I have hereunto set 30 my hand at Grand Rapids, Michigan, this 29th day of January, 1925.

ANDREW EKMAN.
